MATCH BOX

Harold F. Wilhelm, East Orange, N. J.

Application June 20, 1930, Serial No. 462,457
Renewed November 30, 1934

11 Claims. (Cl. 206—33)

This invention relates to match boxes of the type generally made of metal for carrying books of paper matches.

According to the invention a match box is provided having a holding frame for holding a book of paper matches in such manner that an ordinary book of paper matches can be contained in a box fifty per cent smaller than the usual metal match box of similar type. To distort the paper matches, the matches are bent at their junction with the binding or scratching surface of the book in such manner that the matches overlap the binding thereof and are disposed upon the opposite side from the scratching surface.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a perspective of a match box according to the invention in open position showing a distorted book of matches therein;

Fig. 2 is a section on the line 2—2 of Fig. 1;

Fig. 3 is a section on the line 3—3 of Fig. 2;

Fig. 4 is a perspective of a box closed;

Fig. 5 is a section of a modified form of match box;

Fig. 6 is a section illustrating the match box in closed position with the match book in position; and

Fig. 7 is a plan view of the base cover of the box of matches illustrated in Figs. 5 and 6.

In the following description and in the claims parts will be identified by specific names for convenience, but they are intended to be as generic in their application to similar parts as the art will permit.

Like reference characters denote like parts in the several figures of the drawings.

In the drawings accompanying and forming part of this specification, practical commercial embodiments of the invention are shown, but as such illustrations are primarily for purposes of disclosure, it will be understood that the structure may be modified in various respects without departure from the broad spirit and scope of the invention as hereinafter defined and claimed.

Referring now to the drawings and more particularly to Figs. 1 to 4, inclusive, the box comprises a metal case made up of a base cover 1, a top cover 2 connected together by a hinge. The hinge is formed from interfitting knuckles 3 on the covers 1 and 2 through which a pintle 4 is passed.

It will be seen that each cover has a substantially flat bottom with curved sides meeting the sides of the other cover in a pointed edge. The top cover has a lip or catch 5 for engagement with the edge of the base cover to hold the case closed.

Disposed within the case and connected to the base cover 1 is a frame 6 for holding the distorted book of matches. The frame 6 comprises an inclined wall 7 having a depending flange 8. A springy U-shaped portion 12 connects the bottom 6 with a top wall 10 having an elongated opening 11 therein for giving access to the scratching surface of the match book. The upper wall 10 has an inclined lip 9 for assisting in positioning the distorted book of matches and for holding the distorted book after it is positioned. A fire wall indicated by 13 is provided for preventing sparks from jumping from the match as it is struck to the remaining matches in the box.

A holding device such as a rivet indicated by 14 holds the frame 6 fast to the base cover 1.

The book of matches may be the ordinary commercial type comprising an upper layer 20 and a lower layer 21 having portions slitted to form matches 24. The unslotted portions indicated by 22 and 23 are bound together between sheet 26 which is bent around the unslotted portions forming the scratching or striking surface 25. A fastening device 27 passes through the unslotted portions 22 and 23 and the layers of the cover 26 to bind these parts together.

To place the ordinary book of matches in the case the paper cover (not shown) is torn off, all except the part indicated at 26. The matches 24 are bent near their junction with the unslotted portions 22 and 23 near the dotted line indicated by 15. The matches are bent away from the scratching surface 25 and under the unslotted portions 22 and 23 as shown. The book thus distorted is slipped between the bottom 6 and the top wall 10 to the position shown in the figures with the scratching surface 25 being exposed through the opening 11. The inclined bottom 7 together with the inclined position of the top wall 10 so position the matches 24 as to be easily grasped when the case is opened. To detach the

matches they are simply pulled lengthwise of themselves and they easily break at or near the dotted line 15 since they are already considerably weakened by being bent at this point.

5. In the modified form disclosed in Figs. 5, 6 and 7 the base cover is denoted by 30, the top cover by 31, the hinge connecting the covers as denoted by 32 and the catch by 34. These covers may be of substantially the same shape as described above.

10. Positioned in the base cover 30 is a frame indicated by 35. This frame comprises a pair of walls 38 and 39 connected at one end, the wall 39 being provided with an elongated opening 37 to expose the scratching surface 25 of the book of matches. Secured to the walls of the base cover 30 is a pair of ears 33 to which a pair of similar ears on the frame 35 are pivoted by pivots 36.

15. The book of matches is the ordinary commercial book such as described above and like reference characters denote like parts. Disposed in the bottom of the base cover 30 is an inclined plate 42 which is fastened to the cover in any desired manner, such as by soldering. The side 20 wall of the base cover 30 may have a lug or projection 40 adapted to engage in a recess in the frame 35 to yieldably lock the frame in the position shown in Fig. 6. A fire wall 41 is also provided on the frame 35 to prevent sparks from the 25 matches being scratched from reaching the remaining matches in the book.

20. It will be seen that in this modification the frame 35 is arranged to distort the book of matches by being swung from the position in Fig. 5 to the position in Fig. 6. To fill the case with a book of matches it is only necessary to insert the book into the frame 35 as illustrated in Fig. 5 and then to swing the frame about its pivots 36 to the position shown in Fig. 6 until the lug 40 yieldably engages in its recess and the matches 24 are positioned against the inclined plate 42. In this modification, just as in the modification above, the book of matches is so positioned as to permit easy access to the matches 30 when the case is opened.

25. Thus it will be seen that by distorting the book of matches in the above manner a metal match box which is fifty per cent smaller than the usual metal match box will suffice to hold a book of matches. Furthermore, the bending of the matches at the point where they are bound together weakens the paper at this point and assists in breaking off the matches with a full, useful length of shank. In addition the matches are so 35 positioned as to be easily grasped by the fingers and detached, and the provision of the fire wall assists in preventing accidental ignition of the matches by the striking of a match.

30. While certain novel features of the invention have been shown and described and are pointed out in the annexed claims, it will be understood that various omissions, substitutions and changes may be made by those skilled in the art without departing from the spirit of the invention.

35. What is claimed is:—

1. In a match box, a case comprising a base cover, a top cover hinged thereto, a distorted book of matches in said case, said book comprising a striking part and a plurality of matches secured to said striking part, said matches being bent near their junctions with said striking part, said case having means for holding said distorted book therein.
2. In a match box, a case, a distorted book of

30. matches in said case, said book comprising a striking part and a plurality of matches secured to said striking part, said matches being bent near their junctions with said striking part so that they underlie said striking part, said case having means for holding said distorted book therein.

35. 3. In a match box, a case comprising a base cover, a top cover hinged thereto, a distorted book of matches in said case, said book comprising a striking part and a plurality of matches secured to said striking part, said matches being bent near their junctions with said striking part so that they underlie said striking part, and a pocket pivoted to said base cover, said pocket receiving the striking part and operating to distort the book of matches when the pocket is swung down toward the base cover to bend said matches as aforesaid.

40. 4. In a match box, a case, a book of matches in said case having its matches bent back under the striking strip thereof, said case being of such reduced size in plan to accommodate, substantially snugly, a book of matches thus distorted.

45. 5. In a match box, a case, a book of matches in said case, said book having its matches bound together at one end and bent to overlap the binding thereof, said case being of such reduced size to accommodate, substantially snugly, a book of matches thus distorted.

50. 6. In a match box, a case comprising a base cover, a top cover hinged thereto, a distorted book of matches in said case, said book being of the type comprising a plurality of match layers, said layers each having a slotted part to form the matches and an unslotted part, a striking strip on one side of said unslotted parts, means binding said unslotted parts and striking strip together, said matches being bent near their junctions with said unslotted parts away from said striking strip so that they underlie said unslotted parts, said base cover having an inclined surface supporting said matches to space the ends thereof from the bottom of said base cover thereby to make them more easily accessible, said base cover having an inclined pocket for said unslotted parts and striking strip, said pocket having a slot to expose said striking strip when said top cover is opened, and means pivotally mounting said pocket in said base cover.

55. 7. In a match box, a case comprising a base cover, a top cover hinged thereto, a distorted book of matches in said case, said book being of the type comprising a plurality of match layers, said layers each having a slotted part to form the matches and an unslotted part, a striking strip on one side of said unslotted parts, means binding said unslotted parts and striking strip together, said matches being bent near their junctions with said unslotted parts away from said striking strip so that they underlie said unslotted parts, said base cover having a pocket for said unslotted parts and striking strip, said pocket having a slot to expose said striking strip.

60. 8. In a match box, a case comprising a base cover, a top cover hinged thereto, a distorted book of matches in said case, said book being of the type comprising a plurality of match layers, said layers each having a slotted part to form the matches and an unslotted part, a striking strip on one side of said unslotted parts, means binding said unslotted parts and striking strip together, said matches being bent near their junctions with said unslotted parts away from said striking strip so that they underlie said un-

slitted parts, said base cover having an inclined surface supporting said matches to space the ends thereof from the bottom of said base cover thereby to make them more easily accessible, 5 said base cover having an inclined pocket for said unslotted parts and striking strip, said pocket having a slot to expose said striking strip when said top cover is opened.

9. In a match box, a case comprising a base cover, a top cover hinged thereto, a distorted book of matches in said case, said book comprising a plurality of match layers, said layers each having a slotted part to form the matches and an unslotted part, a single sheet bent around said 15 unslotted parts to form a striking strip on one side of said layers and a cover on the other side of said layers, a fastener passing through said unslotted parts and said striking strip and said cover, said matches being bent near their 20 junctions with said unslotted parts away from said striking strip so that they underlie said unslotted parts, said case having means for holding said distorted book in said base cover with the striking strip and matches accessible, where- 25 by said matches will break off near their junc-

tions with said unslotted parts when they are pulled out of the case.

10. In a match box, a case comprising a base cover, a top cover hinged thereto, a distorted book of matches in said case, said book comprising a striking part and a plurality of matches secured to said striking part, said matches being bent near their junctions with said striking part so that they underlie said striking part, a U-shaped spring holder for said distorted book comprising an inclined lower part secured to said base cover and a spring upper part having a slot to expose said striking part, said upper part having a depending abutment to hold said distorted book in place and an inclined lip 15 to assist in inserting said book.

11. In a match box, a case, a book of matches in said case, said book having its matches bound together at one end, said book having parts thereof distorted from their natural shape to reduce the effective size of the book, said case being of such reduced size to accommodate substantially snugly a book of matches thus distorted.
